LOCOMOTIVE STOKER

Original Filed June 4, 1926 2 Sheets-Sheet 2

Inventor:

Nathan M. Lower
By G. L. Nelson, M. M. & Co., Atty's

UNITED STATES PATENT OFFICE

NATHAN M. LOWER, OF PITTSBURGH, PENNSYLVANIA, ASSIGNOR, BY MESNE ASSIGNMENTS, TO THE STANDARD STOKER COMPANY INC., OF NEW YORK, N. Y., A CORPORATION OF DELAWARE

LOCOMOTIVE STOKER

Application filed June 4, 1926, Serial No. 113,800. Renewed September 18, 1929.

The invention relates to the type of stokers in which the fuel is delivered to a distributing nozzle which discharges through the hand firing door opening of the furnace; its objects being to simplify and increase the efficiency thereof.

In the accompanying drawings showing preferred forms of the invention

Fig. 1 is a detail longitudinal vertical section of a locomotive and its tender, with the improved stoker applied thereto;

Fig. 2 is a sectional detail on the line 2—2 of Fig. 1;

Fig. 3 is a detail plan view on the line 3—3 of Fig. 1, some parts being shown in section and some portions being broken away;

Fig. 4 is a detail vertical central section through the rear end of the locomotive, showing a modified form of construction;

Fig. 5 is a section on the line 5—5 of Fig. 4; and

Fig. 6 is a sectional view on the line 6—6 of Fig. 1.

The backhead of the locomotive boiler is represented at 10, and the grate bars of its fire-box 11 are shown at 12. The deck or floor of the locomotive cab is represented at 13, and the tender at 14 which is provided with the usual fuel bin 14a.

The stoker comprises a transfer conduit 15, the rear end of which is upwardly open, as usual, for receiving fuel through a suitable aperture in the floor of the fuel bin of the tender. This conduit extends forwardly as a single inflexible unit to the locomotive and under the deck thereof, its forward end being connected, by means of a ball joint 16, with the lower end of the riser section of an inverted L-shaped delivery nozzle 17. The upper end 18 of this nozzle projects into the hand firing opening 19 in the backhead 10, and delivers upon a distributor plate 20 which projects into the fire-box 11 and from which fuel is swept and scattered over the grate 12 by means of steam jets issuing from nozzles, as 21. Means for advancing the fuel through the conduit 15 may take the form of a screw, as shown at 22.

The rear end of the conduit 15 is mounted on rollers, as 23, which run on tracks 24 se-

cured to the framing of the tender, thereby providing for the movement of the conduit in all directions incident to relative movements of the locomotive and tender, the ball joint 16 cooperating to this end.

The lower leg 25 of the nozzle 17 is preferably rectangular in cross section and preferably flares upwardly, its lower end being substantially of the width of the end of the conduit 15, and its upper end being of the width of the upper section or discharge end 18 of the nozzle, the width of which is approximately that of the door opening 19.

Fuel delivered into the nozzle from the transfer conduit is forced upwardly by the pressure of the advancing element 22, the angular form of the riser conduit checking the tendency of the fuel to rotate with the screw 22. The tendency of fuel to pack in a riser conduit through which it is forced by the continued application of the delivering pressure varies with its character and condition. In order to prevent it in all cases a reciprocating lifter is located within the lower end of the nozzle.

In the construction shown in Fig. 1, this lifter takes the form of a plate 26, pivoted adjacent to the ball joint 16 and swinging upwardly from approximately a horizontal position a sufficient distance to give the fuel an upward impulse and effectually prevent impacting. The free end of the plate 26 is provided with a depending curved skirt 27, which prevents the entrance of fuel back of the plate when the latter is at the end of its upstroke.

In the construction illustrated in Fig. 4, the lifter takes the form of a plunger 28, conforming in shape to the cross section of the lower end of the riser section of the nozzle 17, and reciprocating in a right line, its stroke extending from the bottom of the riser conduit partially across the delivery end of the conduit 15. The plunger 28 is provided with a skirt 29 for preventing fuel from entering below its head.

Motion is transmitted to the lifters 26, 28, by any suitable means. As shown the power is derived from a crank 30 on a shaft driven through a suitable train of gears within the

100

casing 31 connected with the motor 32. Suitable links and levers, as 33, 34, connect the crank 30 with the lifter. The motor 32 supplies power for driving the fuel advancing means, as 22, in the conduit 15, a shaft 35, driven by the motor, being connected with the screw at its rearward end by suitable gearing in a manner that is common in devices of this kind.

10 The distributor plate 20 may be provided on its upper surface with deflecting ribs, as 36, for directing some of the fuel into the back corners of the fire-box. Steam is led to the nozzles 21 through pipes, such as 37, 5 which will be suitably connected to the steam boiler or other source of supply.

15 The stoker is extremely simple, comprising but few parts, two only of which are power driven. The construction described does not 20 exhaust the forms in which the invention may be embodied as it is defined in the appended claims.

I claim as my invention:—

1. In a locomotive stoker, in combination, 25 a fuel delivery nozzle comprising a riser, angular in cross section, located outside of the fire-box of the locomotive, means for delivering fuel to the lower end of the riser under pressure adequate to raise it to the 30 upper end thereof, and a reciprocating lifter in the lower end of the riser for preventing the impacting of the fuel therein.

2. In a locomotive stoker, in combination, 35 a fuel delivery nozzle comprising a riser, angular in cross section, located outside of the fire-box of the locomotive, means for delivering fuel to the lower end of the riser under pressure adequate to raise it to the upper end thereof, and a reciprocating 40 plunger in the lower end of the riser for preventing the impacting of the fuel therein.

3. In a locomotive stoker, in combination, 45 a conduit for conveying fuel from the tender to the locomotive, a delivery nozzle comprising a riser section angular in cross section and connected with the conduit by a ball joint, and a delivery section communicating with an aperture in the back-head of the locomotive fire-box, means within the conduit 50 for advancing fuel through the conduit and forcing it through the nozzle, and a reciprocating lifter within the lower end of the riser section for preventing the impacting of the fuel therein.

55 4. In a locomotive stoker, in combination, a transfer conduit, a riser conduit leading upwardly from the delivery end of the transfer conduit and having its upward end directed forwardly, a screw within the first 60 named conduit for advancing fuel therethrough and forcing it through the riser, and an oscillating plate within the lower end of the riser.

65 5. In combination, a boiler having a firebox, a fuel bin, a stoker including a conduit

for conducting fuel from said bin to said firebox, a helical screw in said conduit for advancing and forcing the fuel therethrough, said conduit comprising sections arranged at an angle, the forward section mounted exteriorly of and opening forwardly into said firebox, and means separate and apart from said screw operating at the juncture only of said sections for preventing impacting of the fuel at said juncture and for assisting in advancing the fuel.

70 6. In combination, a boiler having a firebox, a fuel bin, a fuel feeding conduit system for transferring fuel from said bin and discharging it into said firebox comprising a conveying portion and an elevating portion leading upwardly from said conveying portion exteriorly of said firebox, means within said conveying portion for advancing fuel through said conduit system, and additional fuel advancing means acting upon the fuel adjacent the juncture only of the conveying and elevating conduit portions to prevent the impacting of the fuel and to assist in its conveyance.

75 7. In combination, a boiler having a firebox, a fuel bin rearward of said boiler, a stoker comprising a transfer conduit for conducting fuel forwardly from said bin, a riser conduit exterior of said boiler leading forwardly from the delivery end of the transfer conduit to communicate with said firebox, a distributor member associated with the upper end of said riser conduit, a screw within the first named conduit for advancing fuel therethrough and forcing it through said riser conduit onto said distributor member, and a power actuated member separate from said screw and located within the lower end only of the riser conduit to prevent impacting of the fuel and to assist said screw in advancing the fuel.

80 In testimony whereof I affix my signature.

NATHAN M. LOWER.
